UNITED STATES PATENT OFFICE.

OTTO YETTER, OF BOSTON, MASSACHUSETTS.

STAGING BRACKET.

Application filed April 3, 1924. Serial No. 704,056.

To all whom it may concern:

Be it known that I, OTTO YETTER, a citizen of the United States, and a resident of Boston, in the county of Suffolk and State of Massachusetts, have invented a new and Improved Staging Bracket, of which the following is a full, clear, and exact description.

This invention has relation to supports and has particular reference to a bracket construction for supporting a staging.

The outstanding object of the present invention resides in the provision of a means for supporting a staging adjacent the edge of a roof for effecting repairs to the gutters or the edge of the roof, which supporting means eliminates the necessity of employing expensive scaffolding and the time and labor incident to the erection of the same.

As a further object the invention contemplates a staging supporting means for the purpose set forth which is readily positioned, which is light and easily handled, and which is strong and durable in its construction.

As a still further object the invention comprehends a staging bracket construction which is capable of adjustment to conform both to the pitch of a roof and to variations in the overhang of the roof edge with respect to the side wall of the building.

The invention furthermore contemplates a staging supporting means which is comparatively simple in its construction, inexpensive to manufacture, and which is thoroughly reliable and highly efficient in its purpose.

With the above recited and other objects in view, the invention resides in the novel construction set forth in the following specification, particularly pointed out in the appended claim and illustrated in the accompanying drawings, it being understood that the right is reserved to embodiments other than those actually illustrated herein to the full extent indicated by the general meaning of the terms in which the claim is expressed.

In the drawings—

Figure 1 is a side view of a staging supporting means constructed in accordance with the invention and illustrating the same in applied position.

Fig. 2 is a fragmentary horizontal sectional view taken approximately on the line indicated at 2—2 in Fig. 1.

Fig. 3 is a perspective view of the guard rail supporting means carried by the staging brackets.

Fig. 4 is a perspective view of the adjustable attaching foot forming a part of each bracket.

Fig. 5 is a similar view of an interchangeable foot which is used in connection with each bracket.

Referring to the drawings by characters of reference, the staging supporting means consists of a bracket which includes a vertical member 10 preferably constructed of T. iron, which member is formed with an offset upper end 11 preferably in the form of a gooseneck, the free terminal 12 of which end has eliminated therefrom the flanges and which end is further apertured laterally. A foot 13 having spaced upwardly projecting apertured ears 14 is secured by screws, spikes or other fastening devices 15 which are anchored to the roof after the removal of one or more of the shingles. The apertured extremity 12 of the member 10 is inserted between the ears 14 of the foot, after which a bolt B is passed through the registering apertures in the ears and extremity 12 whereby the member 10 is pivotally connected with the roof. When thus connected the member 10 depends vertically alongside of the side wall of the building. The member 10 has further connected therewith a horizontal member 16 which is preferably of angle iron construction and has a longitudinally adjustable section 17 at its inner end formed with a bearing foot 18 which is designed to engage with the side wall W of the building. In order to render the section 17 adjustable the member 16 is provided with a plurality of longitudinally spaced openings 19 in its vertical flange and the section 17 with a series of longitudinally spaced openings 20 in its vertical flange, which openings, when registered, receive therethrough bolts 21. The opposite outwardly projecting end 22 of the horizontal member 16 is maintained in rigid

position by means of an angle brace 23, the lower end of which is riveted as at 24 to the vertical member 10 and the upper end of which is riveted as at 25 to the vertical flange of the member 16. The horizontal flange of the member 16 at its outer end 22 is turned up as at 26 and the outer end 22

of the vertical flange is turned laterally as at 27 to underlie the horizontal flange. The portions 26 and 27 have riveted thereto as at 28 a vertical strip 29, the upper end of which is turned outwardly at a right angle and is vertically apertured to provide a guide or bearing 30. A second apertured guide 31 is formed intermediate the ends of the strip 29 and the lower end 32 which is turned outwardly is not apertured and forms a stop or rest. A guard rail 33 has connected therewith a depending supporting rod 34, the lower end of which is passed through the aligned apertured guide ears 30 and 31 with the lower extremity resting on the stop or rest 32.

In use of the device the foot 13 of each bracket is first secured to the roof R to coincide with the pitch of the same by heavy screws or spikes driven through apertures in the foot and the free terminal 12 of the upper end 11 of the vertical member 10 is then positioned between the ears 14 of the foot, after which the bolt B is inserted so that the member 10 is pivotally connected with the roof for lateral swinging movement. The section 17 of the horizontal member 16 is then adjusted so that when the foot 18 thereof is in engagement with the side wall W of the building, the vertical member 10 will slightly diverge with respect to the side wall from its upper to its lower end. The staging S is then arranged on the outer end of the horizontal member 16 between the supporting means for the guard rail and the vertical member 10 so that the weight on the staging S is supported both from the roof and the side of the building. When not in use it is, of course, obvious that the guard rail and its supporting rods 33 may be readily disassociated from the brackets by merely lifting up on the same to withdraw the rods 34 from the guide and supporting lugs 30, 31 and 32 and further that the adjustable section 17 of the horizontal member 16 may be disconnected. In

Fig. 5 there has been illustrated a foot member 13^a in which the spaced apertured ears 14^a are arranged transversely to the length of the foot so that the foot member may be arranged longitudinally of the roof when expedient in lieu of the alternative arrangement of the other foot transversely of the roof.

From the foregoing it will thus be seen that a staging bracket which is especially designed for the making of repairs to gutters or points adjacent the edge of a roof has been provided which eliminates expensive scaffolding and gives the workman free access to the parts to be repaired. 55 60

I claim:

A staging bracket for supporting a staging adjacent the edge of a roof comprising a vertical member, a goose neck formed at its upper end, an angularly adjustable attaching foot carried by the free terminal of the goose neck having perforations therein through which attaching means are adapted to be passed for anchoring the same to the roof for suspending the vertical member over the edge of the roof, a horizontal member secured to the vertical member and projecting outwardly away from the wall of the building, an angle brace extending downwardly from the outer end of the horizontal member to the lower end of the vertical member and connected respectively to the outer end of the horizontal member and the lower end of the vertical member and an arm adjustably carried by the horizontal member and projecting inwardly therefrom for engaging the wall of the building in such a manner as to dispose the vertical member in a downwardly diverging relation to the side wall of the building whereby the upper face of the portion of the horizontal member lying between the vertical member and the outer end of said horizontal member is adapted to receive thereon the 70 75 80 85 90 staging.

OTTO YETTER.
